POOL WITH TWIRLING SEESAW

Joseph Diemond, Simsbury, and Leonard E. Greenberg,
West Hartford, Conn., assignors to Coleco Industries,
Inc., Hartford, Conn.

Filed Oct. 27, 1971, Ser. No. 193,228

Term of patent 14 years

Int. Cl. D21—01

U.S. Cl. D34—5 F

FIG. 1

FIG. 2

FIG. 3

FIG. 4

FIG. 5

FIG. 1 is a plan view of a pool with twirling seesaw showing the new design;

FIG. 2 is a side elevational view thereof, the diametrically opposed portion being a mirror image thereof;

FIG. 3 is a side elevational view thereof at a point 90° about its axis from the position illustrated in FIG. 2, the diametrically opposed portion being a mirror image thereof;

FIG. 4 is a bottom view thereof; and

FIG. 5 is a fragmentary sectional view along the line 5-5 of FIG. 1 to show more clearly the seesaw portion of the pool.

We claim:

The ornamental design for a pool with twirling seesaw, as shown and described.
